COMPOSITE SUPERHEATER

Charles W. Gordon, Munster, Ind., assignor to
The Superheater Company, New York, N. Y.

Application April 9, 1932. Serial No. 604,241

5 Claims. (Cl. 122—478)

My invention relates to superheater boilers and more particularly to arrangements with boilers for promoting the use of radiant superheating surface.

5 It is often desired that a superheater boiler deliver steam of high temperature. If, however, all the superheating surface is of the convection type, this may necessitate a very large superheater, while the ordinary radiant type superheater is expensive to install and to maintain. Further, a superheater installation having a portion of its heating surface heated by convection and a portion heated by radiation ordinarily requires double the expense for headers as compared with one of either the radiant heated or convection heated type throughout.

It is the principal object of my invention to provide an arrangement adapted to avoid the above mentioned difficulties.

20 The novel features of my invention are pointed out in the appended claims. In order, however, that my invention, together with its objects and advantages, may be more fully and readily understood, I will now describe in detail and in connection with the accompanying drawing a superheater boiler installation in accordance with my invention and selected by way of example from a number of possible embodiments thereof. In the drawing,

30 Fig. 1 is a vertical sectional view of a superheater boiler in accordance with my invention.

Fig. 2 is a fragmentary sectional view on the line 2—2 of Fig. 1, looking in the direction of the arrows.

35 Fig. 3 is a view similar to Fig. 2, but showing a different arrangement of the superheater units.

The installation illustrated in Figs. 1 and 2 comprises a Stirling type boiler having upper steam and water drums 12 and 14 and a lower 40 water or mud drum 16 connected by a front tube bank 18 and a rear tube bank 20 in the usual manner. The tubes of bank 18 are inclined somewhat to the vertical so as to receive some radiant heat from the furnace chamber 22 which lies below and in front of the bank 18 while their considerable vertical extent creates a high hydrostatic head to cause circulation thru the tubes due to temperature differences in the front and rear banks. As is clearly shown in Fig. 2, the tubes 24, 40 of the bank 18 are arranged in rows parallel to the front of the bank and also in rows in the direction from front to rear of the bank so as to provide clear lanes 26 between such second mentioned rows for the reception of superheater units which are shown at 28, 28 and 29,

29. If, however, the units 28 are arranged so that they have all their heating surface within the lanes 26, a comparatively small amount of heat can be received by such units by radiation. When high degrees of superheat are desired, this 60 leads to an undesirably large superheater and, even when the superheat required of the installation is not above the average, it is evident that the weight of the superheater can be reduced by increasing the amount of radiant heat absorbed 65 by it.

In accordance with my invention, at least some of the superheater surface is supported from the front row of tubes 24 in bank 18 so that such surface receives a high degree of radiant heat together with considerable convection heat. In the arrangement illustrated in Figs. 1 and 2, each water tube 24 in the front row of bank 18 has a lug 30 fixed thereto, preferably by welding. The superheater comprises a header 32 for saturated 75 steam from which steam is taken thru tubes 34, 34 for a group of units which are to receive radiant heat. Tubes 34 run downwardly parallel to the front row of tubes 24 and close to but somewhat in front of such water tubes. Tubes 34 also 80 have fixed thereto lugs 36 which are adapted to be connected to the lugs 30 on water tubes 24 to hold tubes 34 in position. While the lugs 36 secured to the rear face of tubes 34 and 40 and the lugs 30 secured to the front face of tubes 24 85 have been found to be a convenient means of supporting tubes 34 and 40, I do not limit myself to such means. Preferably, lugs 30 and 36 are placed every four feet along the length of tubes 24 over the portion of such tubes having tubes 34 90 parallel thereto. In the arrangement shown in Figs. 1 and 2, moreover, the tubes 34 connect at their lower ends by return bends 38 with tubes 40, 40 which also run parallel to the front row of tubes 24 and have lugs 36 thereon by which 95 they may be connected to lugs 30 and thereby supported from the tubes 24. It is obvious that the tubes 34 or the tubes 34 and 40 may be used singly or in pairs as superheater units largely of the radiant type, but I prefer to combine such 100 tubes with others in superheater units more nearly of the convection type and for this purpose I have illustrated in Fig. 1 a return bend 41 at the upper end of each tube 40 arranged to connect such tube 40 with one or more superheater tubes 42, 42 lying within one of the lanes 26 and back of the front row of tubes 24. As shown in Figs. 1 and 2, there are two such tubes 42 in each front unit 29. For connecting two tubes 42 in a given unit 29, I have illustrated a return bend 105 110

44 at the lower ends of such tubes, the rear tube 42 of each unit 29 being extended upward and connected with the header 46 for superheated steam thru the extension 43. In Figs. 1 and 2, I have 5 illustrated further, additional units 28 wholly of the convection type and each connected by tubular connections 28a and 28b with headers 32 and 46 respectively.

In Fig. 3 there are also two sets of units shown, 10 the rear one of which is composed of units 28a, 28a of the convection type and a set of front units 29a, 29a composed of units receiving a considerable amount of radiant heat. However, whereas units 29 of Figs. 1 and 2 have two tubes in 15 front of the front row of boiler tubes 24, the elements 29a of Fig. 3 each have only one tube in front of the front row of boiler tubes. The arrangement of Fig. 3, therefore, produces a superheater having a characteristic more of the convection type whereas the arrangement of 20 Figs. 1 and 2 produces a superheater having an almost flat load-temperature curve. Since the arrangement of Fig. 3 has only half the number of tubes in front of the tube bank compared with 25 Fig. 2, the lugs 30 may be omitted from every other tube 24 of the front bank and the front tubes 34 of two units 29a suspended on a single tube 24. However, I do not limit myself to this.

It will be seen, moreover, that the tubes 34 and 30 40 and the superheater which lie in front of the front row of tubes 24 are offset somewhat from the centre lines of the lanes 26 so as to overlap the tubes 24. Tubes 34 and 40 therefore are in a position to radiate effectively to the front row 35 of boiler tubes 24 whenever the tubes 34 and 40 are in danger of becoming overheated.

What I claim is:

1. The combination of a vertically inclined bank of boiler tubes arranged in rows to provide 40 lanes therebetween, a superheater having units, 30

portions of which lie within said lanes and portions of which lie in front of the front row of said bank and off-set from said lanes, and means for supporting said front portions of said elements in position to radiate effectively to the tubes in 80 the front row of said bank.

2. The combination as set forth in claim 1 and in which the superheater has two tubes in a given unit parallel to and suspended from a given boiler tube of the front row of the boiler. 85

3. The combination of a bank of semi-vertical generating tubes having lanes therein extending transverse to the face of the bank exposed to the furnace, forwardly projecting lugs fixed to the front faces of the tubes in the front row of said 90 bank, a superheater having certain units arranged principally in said lanes and having certain tubes off-set from said lanes in front of said front row, and means for connecting said front superheater tubes to one of said lugs in position 95 to radiate effectively to the tubes of said front row.

4. The combination as set forth in claim 1 and in which the superheater has one tube of two separate units suspended from a given tube in the front row of boiler tubes. 100

5. The combination of a vertically inclined bank of boiler tubes arranged in rows to provide lanes therebetween, upper and lower drums connected to said tubes, a superheater having units, said units having portions thereof in said 105 lanes and portions in front of the front row of said bank and off-set from said lanes, means for supporting said front portions of said elements in position to radiate effectively to the tubes of the front row of said bank, and headers for said units, 110 the portions of said units leading from said bank to said headers passing in front of said upper drum. 115
